UNITED STATES PATENT OFFICE.

HARRY HUGHES HARRISON, OF LIVERPOOL, ENGLAND, ASSIGNOR TO AUTOMATIC TELEPHONE MANUFACTURING COMPANY, LIMITED, OF LIVERPOOL, ENGLAND.

MULTIPLEX TELEGRAPH SYSTEM.

Application filed May 21, 1924, Serial No. 714,921, and in Great Britain August 10, 1923.

The present invention relates to multiplex telegraph systems and has for its object the extension of the number of channels normally in use by the provision of an arrangement whereby the normal number of channels available in an equal letter system such as five unit code of the Baudot system may be increased without any sacrifice of line time. According to the present invention 5 this is effected by applying the two-power method of signalling, such as is employed in the Morse quadruplex system, to an equal letter system, employing for instance the five unit code of the Baudot system.

10 The two-power method as employed in the Morse quadruplex system consists essentially of superimposing two sets of signals, one being double current signals operating a polarized relay while the other set are single current signals of augmented strength operating a non-polarized relay which is marginally adjusted so as not to operate with the weaker signals of the first set. This system is unsatisfactory in that unless special 15 measures are taken which involve the use of highly complicated and expensive apparatus, signal elements occurring in the two sets of signals will not in general commence at the same instant and hence it will frequently occur that the single current (augmented power) signals will be reversed during a signal owing to the action of the double current signals. If such a reversal takes place during one of the augmented signals 20 the non-polarized relay will momentarily release, the signal will be split, and there will be a tendency to produce distortion.

25 Various devices have been used for bridging this interval of no current but they all have the defect of slightly lengthening the augmented signals since they operate when these signals cease as well as when a reversal takes place during the signal. Furthermore the presence of this no current point fixes a 30 limit to the length of line over which two-power Morse quadruplex operation is possible, since it is necessary to ensure that when the current is reversed the change in sign shall be as rapid as possible. This 35 makes it desirable to have a high voltage for the augmented signals, say two or three times as great as that of the double current signals. In this case the quadruplex circuit is very susceptible to interruption owing to 40 the circuits becoming out of balance, for out

of balance quantities which would have no deleterious effect on the double current signals alone cause serious interference when augmented signals are being transmitted as well, and the double current channel may 45 very soon become unworkable.

According to the present invention, by the application of the two-power method of working to the Baudot system, the signalling elements in both sets of signals commence and terminate together and consequently there can be no splitting in the augmented signals since no current reversal occurs during their transmission. On this account the augmented voltage may be reduced very considerably and the danger of failure from balance variations is very much reduced. Consequently one of the most serious drawbacks of the two-power method 50 of working is overcome and no undue restriction is placed on the length of the line.

A preferred form of carrying the invention into effect will now be considered with reference to the accompanying drawings, although it will be understood that various 55 modifications could be made to the arrangements described without departing from the spirit of the invention.

Fig. 1 of the drawings illustrates the difficulty mentioned with Morse quadruplex 60 working of the two current system.

In Fig. 1, abscissæ represent time and ordinates current and it will be seen that the signal *l* is being sent over the double current channel and the signal *f* over the single current augmented power channel. With the phase relationship of the two sets of signals as shown, it will be observed that at the points marked with a cross the sign of the augmented power signals is reversed and 65 the relay operated by them will therefore momentarily release. If, in order to overcome this defect, means are introduced for bridging this interval as mentioned above, these means will also come into operation 70 at the points *y* thus lengthening the signal slightly.

Two embodiments of the invention will 75 now be described, these being illustrated in Figs. 2 and 3.

Fig. 2 shows how the invention is applied to the sending of two sets of signals simultaneously from station A to station B, apparatus being shown for this direction of 80 working only, though the line is assumed 85

to be duplexed. Rotary distributors TD and RD are provided at the transmitting and receiving ends respectively and any of the usual means well known in the art may be employed for securing that these rotate in synchronism. The solid ring of each distributor is connected to earth and thus the five contact segments corresponding to the five elements of the code are connected to earth in turn by the operation of the rotating brushes. The segments of the transmitting distributor are connected to the contacts of the transmitters TR¹ and TR² which may be of the keyboard or tape controlled type. When the rotating brushes engage the first contact of the set, if the corresponding contact of the transmitter TR¹ is operated, a circuit will be completed for the relay R¹ which will connect up the battery BR to the line L in place of the battery BR¹. Similar results will be produced by other operated contacts of the transmitter TR¹ as the brushes continue to rotate and thus signals are sent out on the two current system which represents normal working. If any of the contacts of the transmitter TR² had been operated however, when the brushes arrived at the appropriate contact, a circuit would be completed for relay R². This then operates to short circuit the series resistance SR and to remove the leak to earth LR, this being a well-known arrangement for increasing the current in quadruplex working. Alternatively also R² could be arranged to insert SR and connect up LR thus decreasing the current.

At the receiving station B the line extends through the non-polarized marginal relay NPR and the polarized relay PR in series, the branch lead from PR extending to the transmitter at the station B for working in the other direction. The relay PR is of the type normally used and is operated in one direction by current of one polarity and is restored by current of opposite polarity. The relay NPR has a biased armature and is only operated by currents of increased strength but of either polarity and is restored to normal as soon as such currents cease to flow.

The relay PR is adapted to complete circuits for a group of printing magnets PMG², from battery B' and to earth by way of the solid ring of the distributor RD, while the relay NPR similarly controls a group of printing magnets PMG¹. Other types of receiving apparatus could clearly be employed if desired. It will then be seen that for each contact of the transmitter TR¹ that is operated, a corresponding operation of the relay PR will take place and hence the corresponding printing magnet in the group PMG² will be operated also. Similarly the printing magnets of the group PMG¹ are operated corresponding to the operated contacts

of the transmitter TR² by the intermediary of the non-polarized relay NPR.

The arrangements for securing simultaneous working in the other direction will follow standard practice and will be readily apparent to those versed in the art.

Referring now to Fig. 3 this shows a slight modification of the previous arrangement whereby one set of signals may be made to operate receiving apparatus while the other set is retransmitted over a line not employing the method of two power signalling.

Only the apparatus at the receiving end is shown, that at the transmitting end being similar to that shown in Fig. 2. Signals coming over the line L¹ traverse the non-polarized relay NPR¹ and the polarized relay PR¹ in series, the lead from PR¹ extending as before to the transmitters for working in the other direction. The relay NPR¹ controls the operation of the group of printing magnets PMG³ as before by way of the solid ring, brushes and contact segments of the receiving distributor RD¹. The relay PR¹ however in this case does not control any printing magnets but repeats ordinary double current signals over a further outgoing line L².

It will of course be necessary in this case that the receiving distributor at the incoming end of the line L² shall rotate in synchronism with the original transmitting distributor at the other end of the line L¹.

It will thus be appreciated that by means of the present invention any of the channels of a Baudot system may be supplemented by the use of a two-power method of working thereover, so that while the line time may normally be fully utilized, additional channels may be made available as and when required without materially affecting the apparatus in use. This arrangement therefore doubles the capacity of any five unit system such as that of Baudot and enables forked and echelon working to be developed to a greater extent than ordinarily.

What I claim is:—

1. A multiplex telegraph system comprising a line, a rotary distributor at the transmitting end of said line, a second rotary distributor at the receiving end of said line adapted to rotate in synchronism with said first distributor, means controlled by said first mentioned distributor for causing currents to flow over said line which may differ in polarity according to one signal to be transmitted, and means also controlled by said first mentioned distributor for causing the currents flowing over said line to be varied in strength according to another signal to be transmitted so that both the signals and the component elements of the signals are transmitted simultaneously.

2. A multiplex telegraph system comprising in combination a telegraph line, two sets

- of transmitting means, a distributing switch connected to the same contacts of which corresponding parts of both said sets are connected, means controlled by one set of transmitting means for sending a current having a particular characteristic, over said line under the control of said distributing switch, means controlled by the other set of transmitting means for sending a current having a characteristic distinct from said first current over said line under the control of said distributing switch simultaneously with the transmission controlled by said first means, a second distributing switch at the receiving end of said line, and two sets of responding means connected to contacts of said switch and adapted to respond respectively under the control of said switch to the two distinctive currents transmitted so as to produce two separate records at said receiving end corresponding to the operation of said sets of transmitting means.
3. A multiplex telegraph system comprising in combination a set of transmitting keys having contacts connected to a distributing switch, a second set of transmitting keys connected to the same contacts of said distributing switch, a telegraph line, a source of electrical energy, means controlled by said distributing switch and said first set of keys for altering the polarity of the current flowing over said line from said source, means controlled by said distributing switch and said second set of transmitting keys for altering the strength of the current flowing over said line, a polarized relay connected to the other end of said line for responding to said changes in polarity, a marginal relay also connected to the other end of said line for responding to said changes in strength, a second distributing switch located at the other end of said line and operated in synchronism with said first distributing switch, a set of recording apparatus controlled by said distributing switch and said polarized relay and a second set of recording apparatus controlled by said distributing switch and said marginal relay so that said first recording apparatus responds to the operation of said first set of transmitting keys and said second recording apparatus responds to the operation of said second set of transmitting keys.
4. A multiplex telegraph system comprising in combination a telegraph line, two sets of transmitting means, a distributing switch to the same contacts of which corresponding parts of both said sets are connected, means controlled by one set of transmitting means for sending a current having a particular characteristic, over said line under the control of said distributing switch, means controlled by the other set of transmitting means for sending a current having a characteristic distinct from said first current over said line under the control of said distributing switch simultaneously with the transmission controlled by said first means, a second distributing switch at the receiving end of said line, two sets of responding means connected to contacts of said switch and adapted to respond respectively under the control of said switch to the two distinctive currents transmitted, a second telegraph line, means controlled by one of said responding means for re-transmitting a distinctive current over said second line, and means controlled by the other of said responding means for causing the signals responded to be recorded.
5. A multiplex telegraph system comprising in combination a telegraph line, a set of transmitting keys having contacts connected to a distributing switch, a second set of transmitting keys connected to the same contacts of said distributing switch, a source of electrical energy, means controlled by said distributing switch and said first set of keys for altering the polarity of the current flowing over said line from said source, means controlled by said distributing switch and said second set of keys for altering the strength of the current flowing over said line, a polarized relay connected to the other end of said line for responding to said changes in polarity, a marginal relay also connected to the other end of said line for responding to said changes in strength, a second distributing switch located at the other end of said line and operated in synchronism with said first distributing switch, a set of recording apparatus controlled by said distributing switch and said polarized relay, a second telegraph line, a second source of electrical energy, and means controlled by said polarized relay for altering the polarity of the current flowing over said second line from said second source.

In testimony whereof I affix my signature.

HARRY HUGHES HARRISON.
